UNITED STATES PATENT OFFICE

HARRY RUBENSTEIN, OF BROOKLYN, NEW YORK

KNITTED FABRIC

Application filed October 15, 1925. Serial No. 62,585.

The invention relates to knitted fabrics and the method of and apparatus for producing the same.

The principal object of the invention, generally stated, is to provide means for and a method of making a knitted fabric possessing certain characteristic features in the arrangement and location of the loops or stitches whereby an unusual and highly attractive appearance will be obtained.

Another object of the invention is to provide, in a circular knitting machine, a novel combination and arrangement of needles, actuating cams therefor and other associated structural elements which will effect the peculiar loop or stitch formation and produce a fabric having the desired characteristics.

A more specific object of the invention is to provide a method of knitting involving the employment of means including different sets of needles arranged in alternation and acting at certain times in alternation and at other times together so as to form loops or stitches all of which are interlinked in a certain peculiar manner to make the fabric.

A further object of the invention is to provide a knitting method and apparatus in which the times at which the needles operate in alternation and the times at which they operate in unison or simultaneously are so related that the interlinked stitches or loops will form a fabric having a somewhat ribbed effect or design.

A still more specific object of the invention is the provision of a knitting method and means for carrying it out including sets of needles having their general features in common but having certain different characteristics whereby certain of the needles will be acted upon by certain cams, others acted upon by different cams, and both acted upon simultaneously by certain other cams so that the successively alternate and simultaneous movement will produce the fabric desired.

To the attainment of the foregoing objects and advantages, the invention consists preferably in the method and the means for carrying it out to be hereinafter more fully de-

scribed and claimed and illustrated in the accompanying drawings in which:

Figure 1 is a somewhat diagrammatic plan view of a circular knitting machine embodying means for producing the fabric, 55

Figure 2 is a magnified view of the fabric produced,

Figure 3 is a vertical section through a portion of the knitting machine illustrating certain mechanical features thereof necessary to the carrying out of the method, 60

Figure 4 is an elevation looking at the inside of the cam means for operating the needles,

Figure 5 is a horizontal section through the cam means taken on the line 5—5 of Figure 4, 65

Figure 6 is a cross section taken on the line 6—6 of Figure 4, looking in the direction of the arrows, and 70

Figure 7 is a cross section taken on the line 7—7 of Figure 4, likewise looking in the direction of the arrows.

Referring to the drawings in detail, I have illustrated, more or less diagrammatically, a portion of a circular knitting machine of a well known type. Only such parts are shown as are necessary for an understanding of the present invention. Machines of this type include a stationary table 1 above 80 which is supported, as by brackets 2, a stationary ring 3 upon which are mounted segmental or arcuate plates 4 which, together, constitute an upper circular ring. Suitably supported with respect to the table 1 is a 85 rotary head 5 travelling within the confines of the ring defined by the plate members 4 and adjacent the inner periphery of a ring 6 stationarily mounted with respect to the table. The head 5 carries the needles to be 90 described which cooperate with cam devices carried by the ring 6.

In carrying out the present invention I make use of two sets of needles arranged in alternation, those of one set being designated by the numeral 7 and having long butts 8 and those of the other set being designated by the numeral 9 and having short butts 10. Except in the matter of length of the butts the needles are all similar and are provided 100

at their upper ends with the usual beards 11 which catch the threads for carrying out the knitting action. Operating between the successive needles are the usual radially movable sinkers or pressers 12 having projections 5 13 thereon engaged within cam grooves 14 in a ring 15 mounted beneath the ring defined by the plates 4, these cam grooves 14 controlling the outward and inward movement of the pressers or sinkers at the proper periodic intervals. Machines of this type are further provided with beard closers 16 for the purpose of closing the beards so that they may enter and pass through the loops of a previously made row of stitches. In actual practice these beard closers are held in place by a circular coil spring 17 which surrounds the head 5 and which engages within notches 18 in the outer edges of the beard closers for 10 holding the beard closers normally away from the path of movement of the beards. It is furthermore customary to provide cams 19 located at intervals and engageable by the beard closers for the purpose of lining them 15 up and retracting them at points in advance of the knitting points, at which latter mentioned points are provided cams 20 for projecting the beard closers outwardly into operative relation to the needles for effecting 20 closing of the beards as the needles move downwardly so that they will pass through previously made loops or stitches and permit the same to be cast off preparatory to making the next successive row. When the machine 25 is in operation all of the needles of course turn with the head 5, the needle butts 8 and 10 being engaged by cam means so as to be moved upwardly and downwardly at the proper intervals.

In carrying out the invention for producing the fabric shown in Figure 2, I arrange the long and short butt needles 7 and 9 in alternation and provide a peculiar cam mechanism cooperating with the butts 8 and 10 30 thereof for effecting knitting with the two sets of needles, at certain times in alternation and at other times together. Referring to Figure 1 it will be observed that the machine is designed to knit with eight threads 35 21, 22, 23, 24, 25, 26, 27 and 28, which threads are led from any suitable source and brought through suitable guides 29 and 30. It will be observed that the number of threads corresponds with the number of cam bearing segments or sections at the plates 4, and at each 40 segment has a knitting point located substantially at the cam 20. The knitting points for the threads 21 to 28 are indicated at 31, 32, 33, 34, 35, 36, 37 and 38, respectively. In 45 the carrying out of the method the long butt needles knit at the points 31 and 33, the short butt needles knit at the points 33 and 37, while both the long and short butt needles knit at the points 32, 34, 36 and 38. 50 While the long butt needles 7 are knitting, at

the points 31 and 35, the short butt needles are idle and remain in lowered position so as not to catch the threads, and while the short butt needles are knitting at the points 33 and 37 the long butt needles are idle and in lowered position. 55

In order to effect this necessary needle movement, I provide cam mechanism which includes sections indicated generally by the numerals 40, 41 and 42, the first named being 60 located at the knitting points 33 and 37, the second named being located at the points 32, 34, 36 and 38 and the last named being located at the points 31 and 35. The section 40 is shown as including a cam 43 having an inclined upper face or shoulder 44 upon which ride both the long and the short butts of the needles. To illustrate the path of movement through the cam sections 40, 41 and 42, I have provided dotted lines 45 and dash lines 46, these two lines representing, respectively, the direction of travel of the short and long butt needles. Located above and extending beyond the cam 43 is a cam 47 having a shoulder or ledge 48 curved downwardly for the purpose of directing the short butt needles to a third cam 49 which is located at the knitting points 33 and 37. The cam 47 has a downwardly inclined shoulder 50 located in the path of travel of the long butts only inasmuch as this shoulder does not project outwardly to a sufficient extent to be engaged by the short butts. The purpose of this shoulder or surface 50 is to move the long butt needles downwardly out of the way and into inoperative position while the short butt needles are knitting. Below the cams 47 and 49 is a cam 51 having a ledge 52 along which the long butts travel after they leave the cam surface 50. The cam 49 has a downwardly inclined edge or surface 53 engaged by the short butt needles after they pass beyond the downwardly curved end 48 of the cam 47 so that the short butt needles will be moved downwardly to perform their knitting action while the long butt needles remain in lowered and inoperative position while passing along the ledge 52. 65

Each of the cam sections 41 located at the points 32, 34, 36 and 38 where both sets of needles knit, includes a cam 54 having an upwardly inclined ledge 55 upon which both the long and short butts engage after leaving the lowest point of the cam 49, this ledge acting to elevate all the needles into position preparatory to making their stitches or loops. In end to end relation to the cam 54 is a cam 56 having a ledge 57 which has one end portion horizontal and acting as a continuation of the higher end of the ledge 55 and which has its other end inclined downwardly as shown at 58. The long and short butt needles ride along the ledges 55, 57 and 58. Above the cams 54 and 56 is a cam 59 spaced somewhat from the ledge 57 so as to guide the 70 75 80 85 90 95 100 105 110 115 120 125 130

needle butts, and one end of the cam 59 has a downwardly curved surface 60 leading to the upper end of an inclined surface 61 on a cam 62, this surface 61 acting to force the needle butts downwardly so that the needles will knit at the points 32, 34, 36 and 38.

The section 42 includes or comprises a cam 63 having an upwardly inclined ledge 64 extending from the lowest portion of the cam 62 and projects only to such an extent as to be in the path of travel of the long butts which will consequently engage thereupon and ride upwardly therealong, the short butts engaging upon a horizontal ledge 65 of the cam member 63 and remaining consequently in lowered or inoperative position. Above the cam 63 is a cam 66 corresponding to the cams 47 and 59 and having a downwardly curved end portion 67 leading to the upper end of a downwardly inclined surface 68 on a cam member 69 corresponding to the cam members 49 and 62. At the end of each section 42 is arranged a section 41. The curved lower edge of the cam 66 coacts with the upper edge of the cam 63 for properly guiding the long butts so that the long butt needles will be held elevated in position to engage and knit the threads. From the above it will be seen that at certain times, all the needles are raised, while at other periods the long and short butt needles are alternately operated to effect knitting.

In the operation, it will be seen that when the head 5 carrying all the needles 7 and 9, 35 the beard closers 16 and the sinkers or pressers 12, is rotated, the beard closers are drawn back away from the needles by the cams 19 located in advance of the knitting points at which are located the cams 49, 62 and 69 for 40 moving the short butt needles, both the long and short butt needles, and the long butt needles alone, respectively, downwardly. The exact manner of thread treatment or handling at the starting of the machine is 45 the same as usual, and assuming that the machine has been operating to a sufficient extent to start the fabric properly, it will be seen that when the butts 10 of the short butt needles 9 come into engagement with the inclined surface 53 of the cam members 49 the short butt needles are moved downwardly. In advance of this point the long butt needles are moved downwardly along the surfaces 50 into inoperative position, as shown by the dash line at the right hand end of Figure 4. 55 As the short butt needles 9 are moved downwardly by the cam 49 the beard closers 16 are forced toward the needles by engagement with the cams 20. The threads 23 and 27 are 60 of course engaged within the beards of the short butt needles and when these needles are moved downwardly the beards will engage the closers 16 and be closed thereby so that the beards, carrying the threads will enter 65 and pass through the loops thus forming

loops 23^a and 27^a. The sinkers or pressers 12 of course operate in the usual well known manner. The threads 21 and 25 engaged by the long butt needles 8 are knitted in exactly the same manner except that the long butt needles are operated by engagement with the inclined edges 68 of the cams 69 in the sections 42, the upper and downward movement resulting in the formation of the loops 21^b and 25^b. The threads 22, 24, 26 and 28 are 70 knitted by both the long and short butt needles, the needles being moved downwardly by engagement with the downwardly inclined surface 61 of the cams 62 in the sections 41, the exact action being the same as above indicated and the loops 22^a, 24^a, 26^a and 28^a being 75 formed by the short butt needles and the loops 22^b, 24^b, 26^b and 28^b being formed by the long butt needles. 80

In actually forming the fabric, the loops 23^a and 27^a are arranged in alternation with the loops 21^b and 25^b of a preceding row, and the loops 22^a, 24^a, 26^a and 28^a are interlinked with the loops 23^a and 27^a, while the loops 22^b, 24^b, 26^b and 28^b are interlinked with the loops 21^b and 25^b as clearly indicated in 90 Figure 2. In this way it is quite evident that the thread between the successive loops 23^a and 27^a and between the successive loops 21^b and 25^b will overlie the body or foundation 95 defined by the interlinking of the threads at those knitting points where both the long and short butt needles operate, thus producing a somewhat ribbed effect such as that illustrated. 100

From the foregoing description and a study of the drawings, it will be seen that I have thus provided a fabric together with a method and means for making the same, embodying certain known principles of design but involving an arrangement of operatively related elements which will produce a fabric possessing certain highly desirable characteristics in the matter of pattern which will be quite distinctive. 105

While I have shown and described the preferred embodiment of the invention, it should be understood that the detailed steps in the method and the specific arrangement, location and correlation of the parts is merely for 115 illustrative purposes only as I reserve the right to make all such changes and modifications as will not depart from the spirit of the invention or the scope of the claim hereunto appended. 110

Having thus described the invention, I 120 claim:

A knitted fabric comprising a plurality of threads in corresponding courses, one knitted at alternate wales and floated at intervening 125 wales in one course, one knitted at every wale of the second course, one knitted at intervening wales and floated at alternate wales of the third course, and one knitted at every wale of the fourth course, the second and 130

fourth threads forming a foundation fabric beneath the staggered floats of the first and third threads, the staggered float relation permitting an equal number of loops in every wale despite the floating of a yarn of a thread which naturally would decrease the loops in a wale.

In testimony whereof I affix my signature.
HARRY RUBENSTEIN.
